MECHANICAL PENCIL

Noboru Wakai, Tokyo, Japan, assignor to Dainihon Bungu Kabushiki Kaisha, also trading as The Japan Stationery Co., Ltd.

Filed Jan. 22, 1970, Ser. No. 21,028

Claims priority, application Japan July 31, 1969

Term of patent 14 years

Int. Cl. D19—06

U.S. Cl. D74—24

FIG. 1

FIG. 2

FIG. 3

FIG. 4

FIG. 5

FIG. 6

FIG. 1 is a front elevation of a mechanical pencil embodying my new design as it appears in closed position; FIG. 2 is a side elevation thereof;

FIG. 3 is a front elevation thereof as it appears with the cap removed therefrom;

FIG. 4 is an enlarged top plan view of FIG. 1;

FIG. 5 is a horizontal cross section on lines 5—5 of FIG. 2;

FIG. 6 is a horizontal cross section on lines 6—6 of FIG. 3.

I claim:

The ornamental design for a mechanical pencil, as shown and described.
